(57) **CLAIM**

The ornamental design for the machine for bill counting and counterfeit detection, as shown and described.

DESCRIPTION

FIG. 1 is a top plan view of a machine for bill counting and counterfeit detection showing my new design;

FIG. 2 is a bottom view thereof;

FIG. 3 is a front view thereof;

FIG. 4 is a rear view thereof, the cord is drawn broken away for ease of illustration;

FIG. 5 is a right view thereof;

FIG. 6 is a left view thereof;

FIG. 7 is a perspective view of my instant invention; and,

FIG. 8 is a perspective view of my instant invention in position to receive bills to be counted.
